DESIGN.

No. 35,032.

Patented Sept. 3, 1901.

I. WANTLING.

ANCHOR FOR DRILLING MACHINES.

(Application filed Aug. 8, 1901.)

UNITED STATES PATENT OFFICE.

ISAAC WANTLING, OF PEORIA, ILLINOIS.

DESIGN FOR AN ANCHOR FOR DRILLING-MACHINES.

SPECIFICATION forming part of Design No. 35,082, dated September 3, 1901.

Application filed August 8, 1901. Serial No. 71,359. Term of patent 7 years.

To all whom it may concern:

Be it known that I, ISAAC WANTLING, a citizen of the United States, residing at Peoria, in the county of Peoria and State of Illinois, have invented a certain new and original Design for Anchors for Drilling-Machines; and I do hereby declare that the following is a full, clear, and exact description of the invention, which will enable others skilled in the art to which it appertains to make and use the same.

Figure 1 is a perspective view of an anchor, showing my design. Fig. 2 is a vertical longitudinal section. Fig. 3 is a plan view, and Fig. 4 is a sectional end view.

As shown in the drawings, the leading or material features of my design consist of an anchor for drilling-machines having a flattened wedge or tapered portion 1, rectangular in shape, and the reduced rounded rear extension 2) and the polygon-shaped extended portion 3, the same being slightly longer than the portion 2 and lies in a plane parallel with

and above the same and tapers off and forms a part of the wedge portion 1.

5 and 6 are substantially semicircular notches or grooves cut in the matching faces of the extensions 2 and 3 and together form parts of a complete circular perforation.

4 is a loop or ring integral with the body of the anchor and is located on the tapered-off portion between the main body of the wedge and the rounded extension 2.

Having described my invention, what I claim as new, and desire to secure by Letters Patent, is—

35 The design for an anchor for drilling-machines as herein shown and described.

In testimony whereof I affix my signature in presence of two witnesses.

ISAAC WANTLING.
